UNITED STATES PATENT OFFICE.

ALVIN W. VAN DORSTON, OF WASHINGTON, DISTRICT OF COLUMBIA.

DRAW-GEAR FOR RAILWAY-CARS.

SPECIFICATION forming part of Letters Patent No. 416,522, dated December 3, 1889.

Application filed June 15, 1889. Serial No. 314,398. (No model.)

To all whom it may concern:

Be it known that I, ALVIN W. VAN DORSTON, a citizen of the United States, residing at Washington, in the District of Columbia, have
5 invented a certain new and useful Improvement in Draw - Gears for Railway - Cars, of which the following is a full, clear, and exact description.

The object of this invention is to take the strain off of the body of the car entirely, or as nearly so as possible, and to distribute the strain upon both ends of the car.

A further object is to provide an improved form of bumper.

15 The invention consists in movable cushioned brackets and followers which receive the draw-bar more or less directly and take the blows and draft upon the same; also, in the combination of similarly equipped draw-bars at opposite ends of the car connected by interposed eveners; also, in the combination of draw-bars at opposite ends of the cars provided with movable cushioned brackets and followers, as described, and connecting eveners, in which eveners are interposed a cushioning medium; also, in the details of construction of the before-mentioned parts, and also in a bumper having a piston or movable head cushioned in an external casing and secured therein by a slot and pin, all as I will proceed now more particularly to set forth and finally claim.

In the accompanying drawings, in the several figures of which like parts are similarly designated, Figure 1 is a plan of my draw-gear broken away in the center. Fig. 2 is a cross-section taken in the plane of line $x\ x$, Fig. 1. Fig. 3 shows in plan and longitudinal section a bracket. Fig. 4 shows in plan and side elevation the piston used in said bracket. Fig. 5 is a plan on a larger scale of one-half of the mechanism shown in Fig. 1, with the bumper in section and with one of the brackets also in partial section and the sleeve and one of the timbers also in partial section. Fig. 6 is a sectional side elevation of one of the longitudinal timbers, showing the arrangement of the brackets and guides for the followers. Fig. 7 is a longitudinal section of the sleeve. Fig. 8 is a detail in elevation of the connecting-rods. Fig. 9 is a side elevation of that end of the connecting-rod

which is attached to the evener-bar. Fig. 10 is a side elevation of modified form of such connection. Fig. 11 is a face view of one of the followers. Fig. 12 is a sectional plan of what is hereinafter designated the "triple gear." Fig. 13 is a transverse section taken in the plane of line $y y$ of Fig. 12. Fig. 14 is a partly sectional side elevation of the coupling for the evener-bar and connecting-rods in the triple-acting gear. Fig. 15 is a side elevation of the cushioned piston for the triple gear. Fig. 16 is a horizontal longitudinal section of a modified form of connection of the draw-head with the followers, and Fig. 17 is a side elevation of the same.

The timbers *a* and *b* may be as usual, and these are connected by longitudinal timbers *c c* in any usual manner. The couplings *d* 70 may be of approved construction, having draw-bars *d'*, to which are pivoted or otherwise attached draw-rods *d²*, which are extended longitudinally between the timbers *c c*. The adjacent faces of the timbers are recessed to receive brackets *e*, which are securely bolted to the timbers. These brackets are provided with pockets *e'*, in the bottoms of which are secured rubber cushions *e²*, as shown in Fig. 75 5, and within the pockets and abutting against the rubber cushions are secured the pistons *f*, and these pistons are retained within the brackets, so as to be freely movable longitudinally therein, by means of bolts *f'*, passing through the brackets and through 80 slots *f²* in the pistons and through the timbers. The projecting portions *e³* of the brackets form wear-plates. Followers *g g* are arranged between the brackets and have laterally-projecting wings *g'*, whose sides bear 85 against the wear-plates of the brackets and whose bases abut against the pistons, and the said followers have cavities *g²*, in which a spring *h* is arranged common to both. The bases of the followers are perforated, as at *g³*, 90 to permit of the passage of the draw-rod *d²*. The spring *h* encircles the draw-rod, and said spring normally tends to separate the followers and hold them against the cushioned pistons *f*. The rear end of the draw-bar abuts 100 against the base of the follower next to it. The followers are retained in position between longitudinal guide-plates *g⁴*, bolted or otherwise secured to the brackets, the said

guide-plates serving to form ways in which the followers travel back and forth under the draft and thrust of the draw-heads. A sleeve *i* is provided with a socket *i'*, into which the rear end of the draw-rod *d*³ is secured, as by means of a key *i*² or other device, passed through the opening *i*^x in the sleeve and through the draw-rod. The sleeve *i* is slotted transversely, as at *i*³, and is provided in said slot with an evener-bar *j*, which is arranged in slots *c'* in the timbers *c*. The evener-bar *j* is provided with a pin or key or other fastening *j'*, which travels in a slot *i*⁴ in the sleeve *i*. The sleeve *i* is arranged slack with relation to the follower next to it, but is adapted to abut against said follower in the movement of the gear. The followers, therefore, with their interposed spring constitute a spring-cushion for the draw-rod, and this spring-cushion is further cushioned by means of the cushioned pistons arranged within the brackets *e*, and the cushioning of the evener-bar within the sleeve *i* completes the cushioning of the draw-bar at every point of its connection with its anchoring or securing devices. A rubber cushion *j*² is interposed between the sleeve and the evener-bar in order to take up shock which would otherwise occur on the evener bar and rods. A tie-bar *k* is arranged beneath the followers and securely fastened to the timbers *c*. (See details, Fig. 2.)

fastened to the timber. (See details, Fig. 2.)

As thus constructed my invention constitutes a single-acting draw-gear; but in a single-acting draw-gear the sleeve *e* may be omitted as also its evener-bar, and the draw-rod may be connected or coupled to the rear-most follower. In order to make a double-acting draw-gear, I connect the evener-bars *j* of opposite ends of the car by means of rods *l*, extending from opposite ends of the evener-bars, and provided with turn-buckles *l'* or other suitable connections. By such addition the draft and also the thrust of the couplers at opposite ends of the car are transmitted from one to the other and upon both ends of the car at the same time.

In order to make this draw-gear triple-acting, I interpose between the evener-bars a double-headed piston m , (see Fig. 12,) and connect the said double-headed piston by means of an evener-bar n with the connecting-rods l of the evener-bars j . The piston-heads of this piston m are arranged within cylinders o , and the bottoms of these cylinders are provided with rubber cushions p , which may have air-valves q . It will be readily understood that in the motions of the draw-gear these cushioned pistons serve to take up the thrust as well as the strain and to take them from the car-body, making the cushioned draw-gear very equable.

Instead of using rubber cushions in the various places in which I have described them as being arranged, I may employ metal springs. I may omit the cushioned brackets altogether and replace them with plain plates; but it will be found that a draw-gear con-

structed in accordance with the first description will be the more desirable and serviceable.

The improved bumper consists of a casing r , which is secured to the timbers by means of a bolt r' , having its head countersunk in the base r^2 of this casing. A rubber cushion s is placed in the bottom of the casing, upon the head of its fastening-bolt, and the movable head t of the bumper is arranged within the cavity containing the cushion s and abutting against the said cushion, and is secured in place therein by means of a bolt t' , passed transversely through the casing r and the head t and a longitudinal slot t^2 in the said movable head. By this construction of the bumper it is firmly secured to the timbers independently of its moving portion, and the said moving portion or head t has a play within the said casing quite independently of the said casing and of the fastening of the said casing. 75 80 85

As shown in Fig. 14, the connections for the evener-bar n with the draw-rods may consist of socket-pieces n' , having central openings n^2 , with transverse intersecting bolt-holes to receive bolts passed through them and through eyes in the ends of the evener-bar. The rods l may be screw-tapped into the ends n^3 of the devices n' , or the connection may be otherwise made.

In Fig. 16 the draw-rod d^2 may be omitted and the draw-bar d' may have formed therewith, but preferably attached thereto, a pocket 3. (See Figs. 16 and 17.) If this pocket is made separate from the draw-bar, it may be secured to the draw-bar by means of gibbs and key d^4 . The pocket receives within it the follower g , between which are interposed the spring or springs h . The spring is compressed by the movement of the rearmost follower and a block or filling-piece d^5 is inserted, behind which is placed a cross-bar d^6 , having dovetailed ends, which are fitted in corresponding openings in the sides of the pocket, and the said bar d^6 and the bar d^5 are securely retained in position by interposed blocks d^7 , fitted between the said bar and the openings in the pocket and on the sides of the bar d^5 . The rearmost follower g may have lugs d^8 extended from its base to embrace the block or bar or plate d^5 ; and, if desired, a pin d^9 may be passed transversely through the bar d^6 and the said ears. Instead of securing the pocket to the draw-bar by means of gibbs and key, bolts may be used. This form of device is particularly well adapted for use in the single-acting draw-gear.

Having fully described my invention, what I claim as new, and desire to secure by Letters Patent, is—

1. A cushioned draw-gear for railway-cars, 130 comprising a draw-bar and draw-rod, spring-followers arranged upon the draw-rod and interposed between the rear end of the draw-rod and the draw-bar, brackets which receive

and support the followers, and cushioned pistons in said brackets, against which said followers abut, substantially as described.

2. A cushioned draw-gear for railway-cars, comprising a draw-bar and draw-rod, spring-followers arranged upon the draw-rod and interposed between its rear end and the draw-bar and movable with the movement of the draw-rod, cushioned brackets provided with pistons against which the said followers abut, and guide-plates for supporting the said followers, substantially as described.

3. The cushioned draw-gear for railway-cars, comprising a draw-bar and draw-rod, brackets secured to the car-timbers and provided with cushioned pistons, guideways connecting the said brackets, followers arranged upon the draw-rod and within the said guideways and next to the cushioned pistons, and a spring interposed between the said followers and normally separating them, substantially as described.

4. The cushioned draw-gear for railway-cars, comprising a draw-bar and draw-rod, a sleeve attached to the rear end of the draw-rod, and an evener-bar pivoted in the sleeve and loosely arranged in the timbers, spring-followers arranged upon the draw-rod and interposed between the draw-bar and the said sleeve and movable with the movement of the draw-rod, and brackets, and cushioned pistons in said brackets to receive said followers, substantially as described.

5. The cushioned draw-gear for railway-cars, comprising a draw-bar and draw-rod, a sleeve attached to the rear end of the draw-rod, and a cushioned evener-bar loosely pivoted in the sleeve and loosely connected to the timbers, spring-followers arranged upon the draw-rod and interposed between the draw-bar and the said sleeve and movable with the movement of the draw-rod, and supports for said followers, substantially as described.

45 6. A cushioned draw-gear for railway-cars, comprising at each end of the car a draw-bar and draw-rod, a sleeve attached to the rear end of the draw-rod, and an evener-bar piv-

oted in the sleeve and loosely connected to the timbers, spring-followers arranged upon the draw-rod and interposed between the draw-bar and the said sleeve and movable with the movement of the draw-rod, and supports for said followers, combined with rods connecting the evener-bars, substantially as described.

7. A cushioned draw-gear for railway-cars, comprising at each end of the car a draw-bar and draw-rod, a sleeve attached to the rear end of the draw-rod, and an evener-bar pivoted in the sleeve and loosely arranged in the timbers, spring-followers arranged upon the draw-rod and interposed between the draw-bar and the said sleeve and movable with the movement of the draw-rod, and supports for said followers, combined with rods connecting the evener-bars, and with a double-headed piston and cushioned cylinders therefor, and an evener-bar connecting the said double-headed piston with the said connecting-bars, substantially as described.

8. A cushioned draw-gear for railway-cars, comprising a draw-bar and draw-rod at each end of the car, and usual or approved mechanisms for taking up the strain and thrust, and evener-bars connected to said mechanisms, combined with a double-headed piston and cylinders therefor interposed between the said evener-bars and connected to their connections, substantially as described.

9. A bumper having a casing, secured to the timbers by means of a bolt whose head is countersunk in its base, combined with a movable head arranged within the casing and secured therein by means of a transverse bolt and a slot in the head, and a rubber cushion interposed between the said movable head and the base of the casing, substantially as described.

In testimony whereof I have hereunto set my hand this 8th day of June, A. D. 1889.

ALVIN W. VAN DORSTON.
